BASE FOR SHOWER, DRINKING FOUNTAIN OR SIMILAR PLUMBING FIXTURES

Thomas M. Vicknair, Walnut Creek, and Richard W. Sargent, San Jose, Calif., assignors to Western Drinking Fountains, Inc., a corporation of California

Filed Nov. 7, 1968, Ser. No. 14,343

Term of patent 14 years

Int. Cl. D23—02, 01
U.S. Cl. D23—70

Fig. 1

Fig. 2

Fig. 3

Fig. 4

FIG. 1 is a perspective view of a base for shower, drinking fountain or similar plumbing fixtures showing our new design;

FIG. 2 is a top plan view thereof;

FIG. 3 is a bottom plan view thereof; and

FIG. 4 is a side elevational view thereof.

We claim:

The ornamental design for a base for shower, drinking fountain or similar plumbing fixtures, as shown.
